UNITED STATES PATENT OFFICE.

HARRY E. CAMPBELL, OF NEW YORK, N. Y.

METAL WINDOW FRAME AND SASH.

1,222,358.

Specification of Letters Patent. Patented Apr. 10, 1917.

original application filed April 19, 1915, Serial No. 22,315. Divided and this application filed August 19, 1915. Serial No. 46,355.

To all whom it may concern:

Be it known that I, HARRY E. CAMPBELL, a citizen of the United States, residing at New York, in the county of New York and 5 State of New York, have invented a certain new and useful Improvement in Metal Window Frames and Sashes, of which the following is a specification.

The invention relates to the construction 10 of metal window-frames and sashes, and more particularly to the combination of sash and frame as more particularly hereinafter set forth.

This application is a division of my pending 15 application Serial No. 22,315, filed April 19, 1915.

In the accompanying drawings—

Figure 1 is an elevation of my window-frame. Fig. 2 is a section of one side of the 20 frame on the line 2, 2 of Fig. 3. Fig. 3 is a section on the line 3, 3 of Fig. 1. Fig. 4 is an enlarged sectional view on the upper sash G, showing a portion of the sash, of one of the guide and bearing-plates and one 25 of the adjustable weather-plates on the sash. Fig. 5 is an elevation of a portion of the sash plates, showing the adjusting means represented in section in Fig. 4.

Similar letters and numbers of reference 30 indicate like parts.

The frame comprises a lintel A, a sill B, two outer jamb plates C, D, and two compartments E, F on the inner side of each jamb plate—the said compartments with 35 their supporting plate forming unitedly a hollow jamb. The upper sash is shown at G and the lower sash at H. As the hollow jambs and associated parts are alike on both sides of the frame, a description of 40 their construction on one side, as shown in Fig. 2, will apply to both sides.

The lintel A has a projection 10, and an opening for the introduction of the suspension device, closed by plate 11. Within said 45 lintel are concave lugs 12, receiving ball-bearings 13 for the journals 14 of the suspension shafts 16 which carry sprocket wheels 17. The sill B is a single casting having an inclined portion 21 to shed water.

C and D are steel plates bent to the form best shown in section in Fig. 2. They are interposed between the sill B and the lintel A and form the outer walls of the hollow jambs. They are held in position by lugs

22, 23 on the lintel and sill. Tie-rods 24 55 bind sill, lintel and jambs together.

I provide on each jamb plate C or D the two weight compartments E, F, constructed in the following manner, Fig. 2. To a flange 25 at one vertical edge of the jamb plate is 60 secured by means of threaded bolts 26 and nuts, a plate 27 bent at right angles and turned over at its edge, as shown at 28. This plate forms two walls of the weight compartment E. At its upper and lower 65 ends it is received between two lugs 29 and a lug 30 on the lintel and sill, the turned over edge 28 lapping over one of the lugs 29.

A second plate 31 similarly bent at right angles and turned over at its edge, as shown 70 at 32, has at its opposite edge a flange 33 which is secured to the jamb plate C by screw bolts 34 which enter a stay bar 35 on the outer side of said jamb plate. The bolts 34 pass through horizontal slots 36, Fig. 3, 75 in flange 33, so that when said bolts are loosened, said plate 31 may be moved laterally upon the jamb plate C. The flange 32 laps over a lug 37 on the lintel and sill. This plate 31 forms two walls of the weight 80 compartment F.

A space is left between the flanged edges 28 and 32 of the plates 27 and 31. The width of said space may be adjusted by moving plate 31 upon the jamb plate as above 85 described. In said space is disposed a baffle-plate 38 which is attached to the jamb plate C by means of an angle-iron welded to said plate and removable bolts 38* passing through said angle-iron and entering the 90 jamb plate. This plate 38 is preferably made thinner than the other plates forming the jamb, so as to be flexible. It forms a partition between compartments E and F. The inner edge of baffle-plate 38 is flanged 95 over, and to said flange is welded a narrow vertical plate 39. The width of said plate is less than the distance between the flanged edges 28, 32 of plates 27, 31, so that clearances are left on each side of said plate 100 39, for a purpose hereafter explained.

The upper sash G has a metal rectangular frame 40.

On the frame 40 of sash G are plates 41, 42, which receive the pane 43, and also a 105 depending flange 44 on lintel A. When the sash is closed, a flange on plate 41 meets the lintel at 45, and the upper edge of plate 42

meets the lintel at 46, so that the joints between said plates and the lintel bottom are not in line.

On the outside of the lower rail of frame 5 40 is welded the plate 47, which forms a meeting rail. A flat plate 48 at its lower edge meets plate 47.

To the side rails of frame 40 are welded wide plates 49, Fig. 2, which enter compartment E through the clearance between the inner plate 27 and the edge of plate 29, and extend outwardly to jamb wall C, Fig. 2.

On the side rails of frame 40 are adjustable weather-plates 50, secured by screws 51.

15 On frame 52 of lower sash H is a meeting rail plate 53 which laps over meeting rail plate 47 of the upper sash. A plate 54 on the lower sash meets the under surface of said meeting rail 53. On the outside of 20 the lower rail of said frame is welded plate 55 which extends below said rail and bears against the vertical face of a shoulder 56 formed on the sill B. On the inside of said lower rail is detachably secured a plate 57, 25 the lower edge of which is flush with the bottom edge of said lower rail, and the inner side of which meets the outer face of a flange 57* on said sill.

On the outside of each vertical side rail 30 of frame 52 is welded a wide plate 58 which enters compartment F through the clearance between the turned over edge 32 of plate 31 and the edge of plate 39 and extends outwardly to the jamb wall C, Fig. 2.

35 On the inner face of each vertical side rail of frame 52 and disposed between the plates 53 and 57 are narrow plates 59, similar to plates 50 on the upper sash and in like manner and by like means adjustable 40 to form a suitable joint with plate 31.

The sashes are hung by sprocket chains 64, 66, which pass around the sprocket wheels 17, and carry weights 65, 67 within the compartments formed in the hollow 45 jambs. The object of making the jambs hollow is, first, to give them structural strength, second, to provide tubular runways for the counter-weights, and third, to enable them to receive the plates 49 and 58.

50 The plate 31 is removable in order to reach the sash weights by withdrawing bolt 34. By removing plate 31, I can easily take out sash H from the frame. Then by taking out bolt 38* which secures baffle-plate 38 55 to outer plate C, I can also easily remove sash G from the frame. By loosening screw bolt 34, I can slide plate 31 upon plate C, and thus adjust the openings receiving the plates 58 and 49 to suit variations in thickness 60 of sash. This I can do best when the plate 38 is, as described, made of less thickness than the other plates, so as to render it flexible. Then when the plate 31 is moved to compensate for a less thickness of sash 65 than is indicated in Fig. 2, the flanged over

edge 32 of said plate pushes against plate 58, thus carrying that plate against the edge of plate 39, which yields because of the flexibility of plate 38, and reduces the width of the opening which receives plate 49 on 70 sash G.

The principal permanent joints are between the vertical edges of wide plates 49, 58 and the inner faces of the jamb plates C, D, and not between the vertical edges of 75 the sash frames and the window frame. Owing to the presence of the baffle-plate 38, which separates compartments E and F, any draft entering through the opening in front of plate 49, for example, would 80 have to travel across the compartment E, through the joint at the edge of plate 49 and then back and escape through the same opening on the rear of plate 49. This, however, is prevented by the weather-plate 50 85 which makes a joint with the plate 39. In order to fit the sash in the frame, all that is necessary is to adjust the edges of the plates 49, 58 to fit against the outer plates C and move the weather-plates 50, 59 to fit against 90 plate 39. Any wear or dislocation due to settlement of the building is easily provided for by similar treatment of the plate edges.

I claim:

1. A metal window-frame, comprising a 95 lintel, a sill and two tubular side members forming jambs, the said side members each having a vertical opening extending through its inner wall, a sash slideable in said frame, and plates laterally projecting from said 100 sash and entering said side members through said openings.

2. A metal window-frame, comprising a 105 lintel, a sill and two tubular side members forming jambs, the said side members each having a vertical opening extending through its inner wall, a sash slideable in said frame, and plates laterally projecting from said 110 sash and entering said side members through said openings and having their outer edges in sliding contact with the outer walls of 115 said side members.

3. A metal window-frame, comprising a 120 lintel, a sill and two tubular side members forming jambs, the said side members each having two vertical openings in its inner walls, an upper sash and a lower sash slideable in said frame, laterally projecting plates on said sashes entering said side members through said openings in said side members, and a vertical partition in each side member disposed between said laterally projecting plates.

4. A metal window-frame, comprising a 125 box-shaped upper transverse member and two tubular side members forming jambs, the said side members each having two vertical openings extending through its inner wall, an upper sash and a lower sash slideable in said frame, laterally projecting 130

- plates on said sashes entering said side members through said openings, a vertical partition in each side member disposed between said openings and dividing each side member into two compartments, counter-weights in said compartments, pulleys within said upper member, and flexible suspension means passing over said pulleys and connected to said counter-weights and said laterally projecting plates on said sashes.
5. A metal window-frame, comprising a lintel, a sill and two tubular side members forming jambs, the said side members each having a vertical opening extending through its inner wall, a sash slideable in said frame, plates laterally projecting from said sash and entering said side members through said openings, and means for varying the width of said openings.
10. 6. A metal window-frame, comprising two tubular side members forming jambs, the said side members each having two vertical openings in its inner wall, and the section of said inner wall between said openings being separate from the remainder of said wall, an upper sash and a lower sash slideable in said frame, laterally projecting plates on said sashes entering said side members through said openings, and a vertical partition in each side member secured at one edge to the outer wall of said member and at its opposite edge carrying said separate wall section.
15. 7. A metal window-frame, comprising an upper box-shaped transverse member and two tubular side members, the said side members each having a vertical opening extending through its inner wall, a sash slideable in said frame, plates laterally projecting from said sash and entering said side members through said openings, and a suspension device for said sash, the said suspension device being connected to said plates and wholly inclosed in said upper member and said side members.
20. 8. A metal window-frame, comprising an upper box-shaped transverse member and two tubular side members, the said side members each having a vertical opening extending through its inner wall, a sash slideable in said frame, plates laterally projecting from said sash and entering said side members through said openings, counter-weights for said sash within said side members, pulleys within said upper member, and flexible suspension means passing over said pulleys and connected to said counter-weights and said laterally projecting plates on said sash.
25. 9. A metal window-frame, comprising an upper box-shaped transverse member and two tubular side members, the said side members each having a vertical opening extending through its inner wall, a sash slideable in said frame, plates laterally projecting from said sash and entering said side members through said openings, counter-weights in said compartments, pulleys within said upper member, and flexible suspension means passing over said pulleys and connected to said counter-weights and said laterally projecting plates on said sash.
30. 10. A metal window-frame, comprising two tubular side members forming jambs, the said side members each having two vertical openings extending through its inner wall, and the section between said openings being separate from the outer sections, means for adjusting one of said outer sections with reference to the middle section, an upper sash and a lower sash slideable in said frame, laterally projecting plates on said sashes entering said side members through said openings, and a laterally flexible vertical partition in each side member secured at one edge to the outer wall of said member and at its opposite edge carrying said separate wall section.
35. 11. A metal window-frame, comprising two tubular side members forming jambs, the said side members each having two vertical openings extending through its inner wall and dividing said wall into three sections, an upper sash and a lower sash slideable in said frame, laterally projecting plates on said sashes entering said side members through said openings, a partition in each side member secured at one edge to the outer wall of said member and at its opposite edge carrying said separate wall section, and laterally adjustable weather-plates on the side rails of said sashes bearing at their outer vertical edges upon the inner wall of said side members.
40. 12. A metal window-frame, having hollow jambs, each comprising an outer wall, two plates secured at their edges to said wall and bent once at right angles toward one another, the said bent over portions lying in the same plane, and a plate forming a partition secured at one edge to said wall, extending into the space between said bent over portions and internally dividing said jambs into two vertical compartments communicating respectively with clearances between the opposite sides of said partition and the opposing edges of said bent over portions, a sash slideable in said frame, and plates laterally projecting from the side rails of said sash and entering said jambs through the clearances on corresponding sides of said partition.
45. 13. A metal window-frame, having hollow jambs, each comprising an outer wall, two plates secured at their edges to said wall and bent once at right angles toward one another, the said bent over portions lying in

- the same plane, and a plate forming a partition secured at one edge to said wall, extending into the space between said bent over portions and internally dividing said jambs 5 into two vertical compartments communicating respectively with clearances between the opposite sides of said partition and the opposing edges of said bent over portions, a sash slideable in said frame, plates laterally 10 projecting from the side rails of said sash and entering said jambs through the clearances on corresponding sides of said partition, and means for varying the width of said clearances.
- 15 14. A metal window-frame, having hollow jambs, each comprising an outer wall, two plates secured at their edges to said wall and bent once at right angles toward one another, the said bent over portions lying 20 in the same plane, a flexible plate forming a partition secured at one edge to said wall and having its opposite edge free and internally dividing the said jambs into two compartments, a plate secured to the free edge of
- 25 said flexible plate and at right angles there-
to and lying in the space between the edges
of the bent over portions of said first-named
plates, there being clearances between said
edges and said interposed plate, an upper
sash and a lower sash slideable in said frame,
30 and plates laterally projecting from the side
rails of said sashes; the said laterally pro-
jecting plates on the upper sash entering the
jambs through the clearances on one side
of said partition, and the laterally project-
ing plates on the lower sash entering said
jambs through the clearances on the opposite
35 side of said partition, and one of said bent
over plates being adjustable with reference
to the other bent over plate to vary the width
40 of said clearances.

In testimony whereof I have affixed my
signature in presence of two witnesses.

HARRY E. CAMPBELL.

Witnesses:

GERTRUDE T. PORTER,
MAY T. McGARRY.

DISCLAIMER.

1,222,358.—*Harry E. Campbell*, New York, N. Y. METAL WINDOW FRAME AND SASH. Patent dated April 10, 1917. Disclaimer filed December 27, 1922, by the assignee, *Campbell Metal Window Corporation*.

Hereby disclaim from said Letters Patent any metal window frame and sash construction except one in which the plates, projecting laterally from the sash into the side members, extend substantially the whole height of such sash, and the portions thereof extending into the side members form the principal permanent joints between the sash and the side members, are the only guide and suspension portions of the sash and are adapted to limit transverse movement of the sash.

[*Official Gazette January 9, 1923.*]
